Primary Examiner — Calvin E Vansant*Assistant Examiner* — Olivia Aldin(74) *Attorney, Agent, or Firm* — Collard & Roe, P.C.(57) **CLAIM**

The ornamental design for a cord lock as shown and described.

DESCRIPTION

FIG. 1 is a top, front and right side perspective view of a cord lock, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom, rear and right side perspective view thereof; and,

FIG. 9 is a top, rear and left side perspective view thereof. The features shown in broken lines depict portions of the cord lock that form no part of the claimed design.
